STEREOTYPE PRINTING PLATE

Martin W. Brueshaber, Chicago, Ill., assignor to
Goss Printing Press Company, Chicago, Ill., a
corporation of Illinois

Application March 13, 1931. Serial No. 522,314

12 Claims. (Cl. 101—375)

The present invention relates to a novel and improved stereotype printing plate, and more particularly to such a plate adapted to be cast at an extremely fast rate.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Figure 1 is a development of the inner surface of a stereotype printing plate in accordance with the present invention, with the showing of the sloping sides of the ribs omitted.

Figure 2 is a horizontal cross section taken through a median portion of the stereotype casting mechanism and showing the stereotype plate of the present invention and the core of the mold in which it was cast.

Figure 3 is a cross-section of the plate taken on the line 3—3 of Figure 1 and showing the plate after it has been shaved to true the inner faces of the ribs.

Figure 4 is a longitudinal section taken on the line 4—4 of Figure 1 and showing the longitudinal ribs formed on the inner surface of the plate.

The increased speed of casting of the modern stereotype casting machine has been accomplished in part through a reduction in the amount of metal contained in the cast plates, thereby reducing the time required for cooling of the plates, as well as reducing the time required for pouring. This reduction in the amount of metal contained in the plate, however, has necessitated making the plates thinner and consequently much weaker and less able to stand the high pressures to which the plate is subjected during the printing operation. The lack of strength of the plate is particularly apparent with plates which contain a large amount of open matter, such as display advertisements composed largely of non-printing areas. The parts of the plate which do not print are, of course, thinner than the printing areas of the plate and these thinner portions

of the plate readily bend under printing pressures.

The present invention has for its object the provision of an unusually strong and rigid, yet thin curved stereotype printing plate which can be cast by automatic casting machinery operating at high speeds. A further object of the invention is the provision of a stereotype plate having an unusual degree of strength which can be finished in the usual stereotype plate finishing machines. Still another object of the invention is the provision of a curved stereotype plate which is not subject to the excessive warping which ordinarily occurs in the cooling of the usual type of thin plates when cast at a high rate.

In accordance with the present invention, the curved stereotype plates illustrative of the invention are of substantially the same thickness as the plates now cast at a high speed, and are provided with additional strengthening means on the rear face of the plates which cooperate to prevent warping of the plates during the rapid cooling. The strengthening means also give added strength to the plates over all its surface but particularly at those points where large open areas occur on the face of the plate, and where the plate is very thin.

Referring now in detail to the accompanying drawings showing the present preferred and illustrative embodiment of the invention, the stereotype plate comprises a substantially semi-cylindrical member provided with a printing face 10, to be inked and printed in the usual manner. As is usual, the printing face comprises raised portions 11 which conform in shape to, and are distributed over the outer surface of the plate, in accordance with the impression to be produced thereby. The open or low portions 12 of the printing face correspond to the white or unprinted portions of the impression to be produced.

On the reverse or inner surface of the stereotype plate are provided the usual circumferential ribs 14 which support the plate on the surface of a printing cylinder during the printing operation. These circumferential ribs are preferably relatively low in height and are provided with divergent sides 15, which thicken the rib near the surface of the plate. These ribs 14 are preferably substantially uniformly spaced, relatively close together and extend from a point closely adjacent to one of the side edges 16 of the plate to a point similarly spaced from the other side edge.

Other circumferential ribs 17, which are of much lower height may be provided in any de-

sired number and are positioned between pairs or other groups of ribs 14, as desired. These ribs serve to strengthen the plate and are not subjected to shaving during the finishing of the plate after casting.

In accordance with the present invention, a series of longitudinally extending ribs 18 are provided which intersect the circumferential ribs and greatly strengthen the plate, permitting the plate 10 to be locked up much more tightly and enabling the press to be run at higher speeds. These ribs also give added rigidity and strength to the plate even at those points where the printing face has no raised or printing portions. These 15 longitudinal ribs in addition to preventing making the plate more rigid during printing render it less susceptible to warping during the extremely rapid cooling of the plate. As embodied, the longitudinal ribs 18 are preferably uniformly 20 spaced, extend axially of the cylinder, from one end of the plate to the other, and are of gradually increasing width from the central portion of the plate to its side edges.

As clearly shown in Figure 1, the inner or rear 25 surface of the plate is provided with a plurality of relatively small recesses 20 of substantially uniform size and shape, each bounded on all its sides by the longitudinal and circumferential ribs 18 and 14.

30 To enable the plate to be shaved in the usual plate-finishing machines and for distributing the cutting load on the shaving knife thereof, the longitudinal ribs 18 are preferably inclined at a very small angle to the axis of the curved plate. The 35 usual shaving knife is set axially of the cylinder and this knife cuts a longitudinal rib 18, engaging the rib over only a very small area at any one time. Preferably, and as embodied, the angle is such that the cutting of one longitudinal rib 40 18 is completed prior to the beginning of the cutting of the next rib.

Figure 2 of the drawings illustrates a core of a typical stereotype plate casting machine, adapted to cast the plates of the present invention. As 45 embodied, the core 22 is water cooled to hasten the cooling of the molten metal after it is run into the mold, thereby reducing the time elapsing between pouring of the metal and the opening of the mold. The core, on its convex face, is provided with grooves which correspond in shape to 50 the desired shape of the ribs on the plate before shaving.

The circumferential ribs 14 are formed by circumferential grooves of the usual form, while 55 the longitudinal ribs 18 are formed by longitudinal grooves 23 in the core. At the front or central portion of the core, the sides of the grooves are slightly converging. The sides of the other grooves also converge at the sides of the core 60 and plate, those at the side edges of the plate being the most convergent. Each groove preferably has its side 25 which is nearest the central portion of the plate extending along a rearwardly and outwardly directed line so that the plate 65 can be easily removed from the core, and the longitudinal ribs 18 at the sides of the plate do not lock with the core.

The depth of the core grooves is slightly in excess of that required for the finished plate, and 70 during the finishing of the plate, the shaving knife reduces the ribs 14 and 18 to a uniform height so that the inner surface of the plate is on a substantially true cylinder.

It will be understood that the foregoing general 75 description and the following detailed de-

scription as well are exemplary and explanatory of the invention but are not restricted thereon.

What I claim is:—

1. A curved stereotype plate having on its inner surface a plurality of substantially circumferential ribs and a plurality of longitudinal ribs. 80

2. A curved stereotype plate having on its inner surface a plurality of substantially circumferential ribs and a plurality of longitudinal ribs, said ribs being substantially uniformly spaced with the circumferential ribs intersecting the longitudinal ribs. 85

3. A curved stereotype plate having on its inner surface a plurality of substantially circumferential ribs and a plurality of longitudinal ribs, 90 said ribs being substantially uniformly spaced and dividing the inner surface of the plate into a plurality of recessed parallelograms.

4. A curved stereotype plate having on its inner surface a plurality of substantially circumferential ribs and a plurality of longitudinally extending ribs, said longitudinal ribs extending at a very slight angle to the axis of the plate. 95

5. A curved stereotype plate having on its inner surface a plurality of longitudinally extending ribs which are inclined at a very slight angle relative to the cutting edge of the knife with which the plates are finished, and a plurality of substantially circumferential ribs intersecting the longitudinal ribs. 100

6. A thin curved stereotype plate having on its inner surface two series of ribs, the ribs of one series extending at right angles to those of the other series and extending substantially from one edge of the plate to the other. 105

7. A thin curved stereotype plate having on its inner surface two series of ribs, the ribs of one series extending at right angles to those of the other series and intersecting therewith and extending substantially from one edge of the plate 110 to the other.

8. A thin curved stereotype plate having on its inner surface two series of ribs, the ribs of one series extending at substantially right angles to those of the other series, the ribs of each series 120 being substantially uniformly spaced and extending substantially from one edge of the plate to the other.

9. A thin curved stereotype plate having on its inner surface two series of ribs, the ribs of one series extending at substantially right angles to those of the other series, the ribs of one series being substantially uniformly spaced, the ribs of the other series being of gradually increasing width away from the central portion of the plate. 125

10. A curved stereotype plate having on its inner surface a plurality of circumferential ribs and a plurality of longitudinally extending ribs, the longitudinal ribs being formed with sides which converge towards the axis of curvature of 135 the plate, the sides nearest to the central portion of the plate converging towards points beyond the outer surface of the plate, whereby the plate can be removed from the mold without distortion.

11. A curved stereotype plate including a plurality of circumferential reenforcing ribs on the back thereof and other reenforcing elements between said circumferential ribs. 140

12. A curved stereotype plate having a back 145 reinforcement comprising a plurality of ribs parallel to the ends thereof and a plurality of ribs parallel to the sides thereof.
